UNITED STATES PATENT OFFICE.

GEORGE C. BLICKENSDERFER, OF ERIE, PENNSYLVANIA, ASSIGNOR TO THE UNITED STATES STORE SERVICE COMPANY, OF ALBANY, NEW YORK.

CONVEYER APPARATUS.

SPECIFICATION forming part of Letters Patent No. 359,957, dated March 22, 1887.

Application filed November 3, 1884. Renewed March 8, 1886. Serial No. 194,509. (No model.)

To all whom it may concern:

Be it known that I, GEORGE C. BLICKENSDERFER, a citizen of the United States, residing at Erie, in the county of Erie and State of Pennsylvania, have invented certain new and useful Improvements in Conveyer Apparatus; and I do hereby declare the following to be a full, clear, and exact description of the invention, such as will enable others skilled in the art to which it appertains to make and use the same.

This invention relates to that class of conveyers in which the track is suspended or otherwise sustained in an elevated position, and the car or article to be conveyed hangs pendent from a running-gear which rests upon said track, which class of conveyers includes within it what are known as "store-service systems."

My invention consists in improvements in the construction of the track and its arrangement in the store or room in which it is applied; also, in improvements in the construction of the switches and means by which cars are received from the track at the stations, let down to the person in charge at the station, and elevated to the track for reshipment, and the means for reshipping or dispatching the cars on the track; also, in improvements in the construction of the cars and other details.

In the accompanying drawings the invention is shown as applied to a store-service system, and will be so described and referred to in the following description; but it may be applied to various other services without difficulty or any material change or modification of parts.

It is common in this class of conveyers to have two tracks graded in opposite directions—one of which grades from the central station or cashier's desk to the salesmen's stations, and the other grades toward the cashier's desk from the salesmen's stations—and at the several stations to have means for receiving the car from one line or track and dispatching it on the other.

The leading feature of this invention consists in having but one track which grades in one direction and starts from the central station and makes a circuit of the whole or a part

of the store, as desired, and returns to the central station, and in providing at each station in the circuit means for receiving cars destined to it from the track and reshipping them upon it without interfering with the passage of cars destined to other stations.

The accompanying drawings illustrate my invention, as follows:

Figure 1 is a diagram showing the arrangement of track-circuits, stations, and cashier's desk in a large store. Fig. 2 is a perspective view of one of the stations, showing a car as just received. Fig. 3 illustrates the action of the elevator as it starts to descend and carry the car down to the counter. Fig. 4 shows the elevator down. Fig. 5 shows the elevator drawn up to the full extent and in the position it occupies when dispatching a car. Fig. 6 is an end view of a car entering a station, the track A' being in section on the line x x in Fig. 5, the direction of vision being shown by the arrow. Fig. 7 is a perspective view of the parts as seen in Fig. 6. Fig. 8 is a perspective view, and shows a curve or corner on the line of track, and on the right of the figure the terminus of the line at the cashier's desk. Fig. 9 is an end view of a car as it is running upon a curve, and shows the arrangement of the curve fender-bar A'. Fig. 10 is a top view of a terminus curve at the cashier's desk. Fig. 11 is a side elevation of the parts shown in Fig. 10. Fig. 12 is a side elevation of the running-gear of a car. Fig. 13 is an end elevation of the parts shown in Fig. 12; Fig. 14, a view, part elevation and part section, of one of the wall-anchors by which the track-line is supported at the angles and ends. Fig. 15 is a top view of one of the curve-track-supporting irons. Fig. 16 is a side view of the same.

In the drawings, A marks the main tracks, which in Fig. 1 grade in the direction of the arrows, and are arranged in three separate circuits.

A' marks the receiving switch-track at the stations, and A² the dispatching switch-track.

B marks the vertical guide-bar or track of the elevator.

B' marks a fixed arm on the bar B, by which the receiving switch-track A' is supported at its inner end.

C marks a sliding block which moves on the bar B.

C' marks an arm which is pivoted to the block C and connected with the discharging switch-track A², which is pivoted at its outer end at a² to the arch-iron A³, so as to allow of vertical movement, so that as the block C is moved up or down the grade of the switch-track A² is changed.

10 D D' mark the elevator-frame, of which D is a slide on the bar B, and D' is an arm which supports a section of track, D², on which the cars are received from the switch-track A¹, as seen in Fig. 1, and from which the cars are discharged onto the dispatching switch-track A², as is shown to have been done in Fig. 5.

G is the cord by which the elevator is manipulated.

H marks the car, and H' and H² the wheels 20 of the car.

The other designations by letters will be referred to in proper place in the following description.

I have stated above that the leading feature 25 of this invention consists in the use of a single track arranged in a circuit and means for receiving and discharging cars from said track at each of the stations.

In Fig. 1 I illustrate by diagram a system 30 of said circuitous tracks and such an arrangement or disposition thereof as to afford communication to all parts of a large store. The store shown is a double-aisle store, and the central station or cashier's desk is placed at one end.

The forms of stores and their arrangement are so various that it would be impracticable 35 for me to illustrate the arrangement necessary for all; but from the diagram it can be understood how by a proper arrangement of circuit all forms and designs of stores can be supplied with service. For example, if a store has but one aisle, and it is not too long, a single circuit like circuit 1 in aisle 1 will afford service to all parts. If it is too long to use one circuit without two much time being consumed in cars making a run of the circuit, then the cashier's desk may be located midway in the 40 store, and two circuits—one running each way

45 from it—will afford proper service. If on one of these circuits there is so much business done that the line will be overcrowded, a short circuit may be added to receive part of the traffic. This is shown in aisle 2, where circuit 50 2 serves one end of the aisle and circuit 3 the other end, and both circuits run to the cashier's desk at one end. Such an arrangement as this will be found desirable where the arrangement of the goods on the shelves is in departments.

55 For instance, we will suppose that in aisle 2 the departments in that part of the aisle served by circuit 3 are those in which the most sales in number are made, which would be the case if the goods in that space were such as fancy articles, notions, &c., while in the remaining space of the aisle the sales are less frequent. With such a condition of affairs the service in

the space occupied by circuit 3 should be more rapid than in the other space, and by the use of the short circuit it would be made twice as 70 rapid as where one circuit alone is used; and if the grade of the short circuit is made greater than the long circuit, which can be the case if the character of the article is such that the cars will not be heavily loaded, the rapidity of 75 service may be increased still more for that space.

The advantages of the one-line circuit systems over the former double-line direct systems are numerous, among them being cheapness of 80 construction, less incumbrance of store-space, simplicity of action, and fewer converging tracks at the central station, and hence less difficulty in attending to the reception and dispatch of cars and less liability of confusion 85 and misdirection of cars at that station. While it will appear at first thought that a given number of stations arranged on opposite sides of an aisle would be served more rapidly by two double-track systems—one on 90 each side of the aisle—than by a single-line circuit which takes in all of the stations, as a matter of fact, in actual practice there is very little, if any, difference, and the advantages in favor of the one-line circuit system more than 95 compensate for such slight loss of time as there may be.

The use of a one-line circuit is made possible by the provision of means by which the cars can be received from the main track at 100 the stations, let down to the attendant, and raised up again to and dispatched on the track.

To operate properly, and at all times leave the main track open for the passage of cars not destined to the station, these means should 105 consist of a receiving switch-track, a discharging switch-track, and an elevator device; but where the service is such or the position of the track is such that it is not required that the cars be lowered to the attendant at the station, 110 of course the elevator device may be omitted.

The construction, adjustment, and method of operation of the elements above named may of course be varied greatly and effect the desired results without materially changing 115 the essential features.

It would be impracticable for me to illustrate all the modified constructions which would embody said essential elements and functions which may be made practicable; but I have shown a construction which is entirely sufficient for the purposes named and fully embodies my invention.

Figs. 2, 3, 4, and 5 illustrate the construction and operation of the station appliances. 125 A is the main track, and is shown as graded from left to right. A' is the incoming or receiving-switch track. This has its inner end firmly secured to the arm B', and its point is fixed to an arch-piece like A³. (Not seen.) 130 A² is the outgoing or dispatching switch track, and is pivoted to the arch-piece A³ at a², and is fixed to an arm, C', which is pivoted to the slide C. These switches are arranged below

the track and intended for cars with tripping-wheels, such as is shown in Letters Patent is-
sued to me September 23, 1884; but I do not
wish to be understood as thereby implying
5 that my present invention is limited in its scope
to the use of such cars, for the construction can
be modified to adapt it to other forms of
switches and cars. On the arm D' of the ele-
vator-frame is a section of track, D².

10 Fig. 2 shows the elevator-frame in such a po-
sition as to bring the track-section D² in line
with the switch A', and the illustration shows
a car as it is received by the elevator. E is a
draw-bar, which passes through the track sec-
15 tion or bar D², and serves as a stop to stop the
car in the position shown. The bar or track
D², it should be remembered, is set at an in-
cline about the same as the track-grade. On
the arm B' there is pivoted a stop, B² B³, which,
20 when not depressed by the elevator-bar D²,
keeps in the position shown in Fig. 4, and
serves to stop the car on the track A'. This
stop is formed of two parts, B² and B³, both
hung on the same pivot, b², and the arrange-
25 ment is such that the part B³ can be raised in-
dependent of the part B², but when depressed
it moves the part B² with it. The object of
this is to allow the elevator-bar to pass up into
the position shown in Fig. 5. The bar D² has
30 a rule-joint at d, which allows it to be raised,
as seen in Fig. 3, so it can go down past the
stops B² B³ into the position shown in Fig.
4. On the back of the arm B' is a catch-lug,
B⁴, and on the elevator-slide D there is a catch-
35 bar, D³, kept in place by a spring, d³. This
catch-bar engages with the catch-lug B⁴ and
holds the elevor in the position shown in Fig.
2, which, as before stated, is the position for
receiving cars from the switch-track A'. When
40 the parts are in this position, it will be seen
that it holds the stop B² B³ depressed, so a car
can run onto the switch. After a car is re-
ceived it must be lowered down to the counter.
To do this the attendant draws with the cord
45 G against the catch-lever D³ and throws it off
the catch B⁴, and this allows the elevator to
descend, and as it does so the bar D² bends at
its joint d and slips off the stop B² B³, as seen
in Fig. 3. Fig. 4 shows the elevator down.
50 After the car has been refilled and is to be dis-
patched the elevator is drawn up. As it
passes up the catch-bar D³ slips over the catch-
lug B⁴, and the end of the bar D² lifts the part
B³ of the stop B² B³ and passes by it, and the
55 elevator-frame abuts against the slide-block C
and carries it up along with it, and the parts
are brought into the position shown in Fig. 5.

On the block C is a lever, C², which has the
60 general form of a bell-crank lever. As the
elevator goes up the long end of the lever C²
passes back of the bent outer end of the draw-
bar E, and when the parts reach the position
shown in Fig. 5 the short end of the lever C²
is brought in contact with and depressed by
65 the stop-block C², and this action throws out
the lower end of the lever and draws back the
draw-bar. This action releases the car, and

it runs off the bar D² onto the switch-track A²,
and its upper wheels are guided by the guides
a a on the arch-piece A³, so that they come 70
upon the track A as the lower wheels, H², run
off of the end of the switch A². The switch-
track A², when in the position shown in Fig.
5, is quite steep, and the car passes off it
quickly onto the main track. When the car 75
has passed off onto the main line, the elevator
is lowered into the position shown in Fig. 2.
When the elevator is thus lowered, the slide-
block C drops down the length of the suspending-
rod e, which moves in a hole in the stop-
block C². As soon as the elevator moves down
the draw-bar E is released from the lever C²,
80 and is reacted by a spring, E', so that it is in
position to serve as a stop. When the slide-
block C is down in the position shown in Figs. 85
2 and 4, the track A² is out of the way of cars
passing on the main line. This pivoted switch-
track A², I use for dispatching cars in systems
where oppositely-graded tracks are used, and
shall illustrate such use in an application to be 90
filed by me at a future date. It is a very im-
portant feature, and I do not wish to be un-
derstood as here limiting its use to a one-line
circuit system.

Figs. 6 and 7 show a car passing along the 95
track A'. These figures, together with Figs.
10 and 11, illustrate a braking device for
checking the speed of the car before it runs
onto the elevator or is stopped by the stop B²
B³, and in Figs. 10 and 11 the device serves 100
to gradually stop the car as it runs into the
central station. It consists of a rave, F, along
the side of the track and below it, where it will
come in contact with a projection, F' or F², on
the car-frame, as the case may be. (On the 105
switches it is the projection F' which is em-
ployed, and in entering the central station it
is the projection F².) At the switches the
rave is so placed as to just clear the projection
F' when the car is standing perfectly still, as 110
seen in Fig. 6, and as a car which is moving
rapidly, and especially one which has just
turned onto a side switch, has a more or less
vibratory movement, the rave and the projec-
tion will come in contact and produce friction 115
sufficient to check the speed of the car, but not
entirely stop it, so that it will pass onto the
elevator slowly. At the central station, as
shown in Figs. 10 and 11, the rave is so ar-
ranged as to at first strike the projection F², 120
as the car swings, and finally to fully engage
it, thus first checking the speed of the car and
then fully stopping it. Figs. 10 and 11 show
a curved track, A⁶, for carrying the cars off
the wire line A into the station. This con-
struction is sometimes made necessary by the 125
surroundings. At the right of Fig. 8 another
form of car-stopping device is shown. It con-
sists of the wire K, arranged below the track
A in such a position as to wedge in between 130
the wheels H' and H² as the car approaches
the post P, and thus stop the car and hold it
from rebounding.

At the left of Fig. 8 and in Fig. 9 I illus-

trate the construction and operation of a curve guard or fender. As cars pass around curves they have imparted to them a swinging motion, by reason of the centrifugal force generated by their passage around the curve, and if the cars are loaded heavily or run rapidly this vibratory motion will be so great as to give an unsteady action to the car, and also impart a vibratory action to the whole line of track, especially when the track is formed of a taut wire. To prevent this action I attach to the outside of the curve-track A⁴ by hangers a⁵ a fender or guard-rail, A⁵, and on the cars I put friction-rollers H³ H³, which will bear against the rail A⁵ as the car runs around the curve and prevent it swinging beyond its center of gravity by the centrifugal action. The result of this device is that the cars move off on the main line after passing a curve without swinging and run true and steady.

In erecting and supporting a track made of a taut wire it is necessary to use guys at the angles, and where these guys have to be connected with the wall of a brick or stone building an anchor device is required. In Fig. 14 I show the construction of the anchor I use. It is also seen in Fig. 8, and marked with the letter L. It consists of a ring, (or hook, if desired,) l, and wall-plate l', which I show to be one piece of metal, a tube, l², wings l³, bolt l⁴, and expanding head l⁵. The bolt is screw-threaded on its outer end, and the wall-plate and hook or ring screw onto the bolt. The wings l³ are connected with the inner end of the tube by hooks, and the expanding head is a part of the bolt l⁴, and as the bolt is drawn into the tube by the turning of the nut (which is the ring and wall-plate) the wings are expanded. The device is applied by drilling a hole into the wall, inserting the device, as shown in Fig. 14, and turning the nut until the wings are expanded, so as to firmly hold the anchor in the wall.

In place of the ring and wall-plate serving as a nut, a separate nut may be used, in which case the wall-plate will serve as a washer back of the nut, or the ring and wall-plate may be separate pieces, the former serving as a nut and the latter as a washer. At points on the line where curve-tracks spring from it there is an attaching-iron connected with the wire track A, by means of which the curve-track bars are secured. This device is shown in detail in Figs. 15 and 16, of which the former is a top and the latter a side view. It is marked by the letter I, and consists of a casting having an eye at each end and a seat for the end of the curve-bar A⁴ and screw-holes i i for securing the curve-bar to it. The track A has its end bent and screw-threaded, and it is inserted through the eye i nearest the curve-bar seat, and a nut, N, secures it.

It is of course not essential that a nut be used on the end of the track A, for it may be secured in place by clinching or otherwise; but its end cannot be wrapped over, as is the guy-line at the other end of the iron I, for that

would interfere with the passage of the cars. This iron serves the same purpose as one shown and claimed in Letters Patent of the United States No. 295,478, issued to myself and H. Smith; but its construction is different, as in that case the wire track is not broken, but passes through the iron.

The car used is substantially the same as shown in a patent granted to me September 23, 1884, and I need here only describe such improvements as I here make in its construction. These are illustrated in Figs. 12 and 13. These improvements relate to the construction and adjustment of the means for tripping the upper wheels. The upper or main-track wheels are on T-shaped frame-piece H⁵, which slides upon the standard H⁴ of the car-frame. It is moved up when the wheels are tripped, as the car passes upon a switch, by a spring, H⁶, and it is held down by a catch trigger, T, which is pivoted on a pin, h⁴, which extends from the standard H⁴ through a slot in the slide H⁵, and catches upon a pin, h⁵, which extends from said slide. The catch-trigger is reacted by a spring and is disengaged by the lever T' coming in contact with an arm at the switch-points, as described in said former patent. The lever T' is made adjustable as to height, and is secured at any height by a binding-screw, t. The lever T' is provided with an index or mark, and on the face of the slide H⁵, back of it, is a scale, S, on which are the numbers of the stations on the line. The arms at the switch-points against which the trigger-lever strikes to spring the trigger are fixed at regular graded heights, to correspond with the spaces of the scale S, and thus the trigger of any car can be quickly adjusted so that said car will be switched at any desired station. The scale S might be on the lever T' as well as on the face of the slide H⁵. This arrangement is very convenient and will be of great utility in conveyer systems where the same car is sent to different stations—such, for example, as hay, coal, or slaughter-house conveyers. It will also be useful in store-service systems, as by it extra cars can be kept at the cashier's desk, which can be thrown into use for any station, if desired.

It often occurs that cars run against each other, and it is therefore desirable that they be provided with buffers.

In Figs. 5, 6, 7, 9, and 11 there will be observed at the ends of the car-frames a bent metallic plate, J. When two cars run together, these plates receive the shock and serve as buffers, and prevent the car bodies or frames hitting against each other.

What I claim as new is—

1. In a conveyer apparatus, the combination, substantially as set forth, of a main or central station, a series of way or local stations, a circuit of track grading from the main station past all the way-stations and back to the main station, a car-elevator at each of said way-stations, and shunts or switches which receive cars from the track-circuit and con-

vey them to the elevator, and which also dispatch them upon the said track-circuit.

2. In a conveyer apparatus, the combination, substantially as set forth, of a main or central station, a series of way-stations, a circuit of track which grades from the central station past all the way-stations and back to the main station, a car-elevator at each of said way-stations, a switch or shunt at each way-station which leads from the track-circuit to the elevator and back to the track from the elevator, which switches have their points in a substantially vertical plane with the main track, and, finally, cars which are provided with two sets of wheels, one for action on the main track and the other for action on the switch-tracks and elevators.

3. A conveyer apparatus comprising, substantially as set forth, a main or central station, two or more track-circuits which grade from said main station and back to it and are of differing lengths, the shorter of which traverse part of the space traversed by the longer, and each connects with a separate series of way-stations, and shunts or switches on each of said circuits at each of the stations thereon for receiving cars from and dispatching them upon the said continuous main line.

4. In a conveyer apparatus, the combination, substantially as herein set forth, of a continuous main track, a switch or shunt track leading from said main track, a section of vertically-movable track to receive cars from the said shunt-track, and a second shunt-track which leads back to the main track and receives cars from said vertically-movable track-section when it is elevated and conducts them onto the said continuous main track.

5. In a conveyer apparatus, the combination, substantially as set forth, of a continuous main track, cars provided with two sets of wheels, one for use on said main track and the other on the shunt or switch tracks, a receiving switch or shunt track which is placed so as to engage the said switch-wheels and conduct the cars away from the main track, a section of vertically-movable track to receive cars from said receiving switch-track, and a second switch-track which receives cars from said vertically-movable track-section when elevated and conducts them to and replaces them with their main wheels upon said continuous main track.

6. In a conveyer apparatus, the combination, substantially as set forth, of a continuous main track, cars provided with two sets of wheels, one for use on the main track and the other on the switch-tracks, which sets of wheels are arranged one above the other, a receiving switch or shunt track which has its point arranged in a substantially vertical plane with the main track and in position to engage the switch-wheels of the car and conduct the cars away from the main track, a section of vertically-movable track to receive cars from the said receiving switch-track, and a second switch-track which will receive cars from the

said vertically-movable track-section when elevated and conduct them to and replace them with their main wheels upon said continuous main track.

7. In a conveyer apparatus, the combination, substantially as set forth, of a main line of track, a shunt or switch track leading from said main track, a vertically-movable track-section for receiving cars from said shunt-track, and a second shunt-track which leads back to the main track, and is pivoted at its point and vertically movable at its inner end with the said vertically-movable track-section, and which will receive cars from said track-section when it is elevated and conduct them to the main track.

8. In a conveyer apparatus, the combination, substantially as set forth, of a main track, a switch-track leading from the main track to an elevator, an elevator having thereon a section of track which receives cars from the switch-track, and a second switch-track which leads from the elevator to the main track, and is pivoted at its point and movable vertically at its inner end by the action of the elevator, and receives cars from the elevator and conducts them to the main track.

9. In a conveyer apparatus, the combination, substantially as set forth, of a main track, a switch-track leading from the main track to an elevator, an elevator which is provided with a section of track on which cars are received from the said switch-track and by which the said car can be let down to the attendant, a second switch-track which conducts cars from the elevator to the main track and is pivoted at its point, so as to allow of vertical movement at its inner end, and a vertically-movable slide which is connected with the inner end of the said last-named switch and is moved vertically by the action of the elevator.

10. In a conveyer apparatus, the combination, substantially as described, of a main track which grades from a central station past a series of way-stations and returns to the said central station, an elevator at each station which slides on a vertical way and carries a section of track on an arm, a receiving switch-track which conducts cars from the main track onto the track-section on the elevator, and a dispatching-switch which conducts cars from the said track-section on the elevator back to and replaces them upon said continuous main track.

11. In a conveyer apparatus, the combination, substantially as set forth, of a main track which forms a circuit which includes within it a series of stations, an elevator at each of said stations which slides on a vertical way and carries a section of track on an arm, a receiving switch-track which conducts cars from the main track onto the track-section on the elevator, a vertically-moving slide on the elevator-way which is moved by contact with the elevator, and a dispatching-switch which is pivoted at its point and is pivotally connected

with and moved vertically by the said slide at its inner end, so as to change its grade.

12. In a conveyer apparatus, the combination, substantially as set forth, of the main track A, the receiving-switch A', the dispatching-switch A², the switch-point support A³, the pivot a², the guides a a, the vertical slide-way B, the switch-supporting arm or bracket B', the slide C, the pivoted switch-supporting arm C', the elevator-slide D, with arm D', the track-section D², supported by said arm, and the car H, with main-track wheels H' and switch-track wheels H².

13. In a conveyer apparatus, the combination, substantially as set forth, of the main track A, the receiving-switch A', the automatic car-stop B² B³, the supporting-arm B', the elevator-guideway B, the catch-lug B⁴, the elevator-frame D D', the track-section D², secured to the elevator and jointed at d, the catch-lever D², the elevator-cord G, the slide-block C, the stop-block C², the pivoted switch-supporting arm C', the dispatching-switch A², pivoted at a², the switch-supporting arch A³, the guides a a, and the car H, with wheels H' H' and H² H².

14. In a conveyer apparatus, the combination, substantially as set forth, of the main track A, the receiving switch-track A', the automatic car-stop B² B³, the switch-supporting arm B', the catch-lug B⁴, the guide-bar B, the elevator-frame D D', the car-receiving track-section D², jointed at d, the catch-bar D³, the elevator-cord G, the draw-bar stop E, the sliding block C, the draw-bar-moving lever C³, the stop-block C², the pivoted switch-supporting arm C', the dispatching switch-track A², pivoted at a², the switch-supporting arch A³, the guides a a, and the car H, with wheels H' H' and H² H².

15. In a conveyer apparatus, the combination, substantially as set forth, of a main track, a car-elevator by the side of said main track, a car-supporting track-section on said elevator, and a dispatching-switch which is pivoted near its point, so that it can have vertical movement at its inner end to change its grade, and is arranged, substantially as set forth, to be operated vertically by the said car-elevator and to receive cars from the said track-section on the elevator.

16. In a conveyer apparatus, the combination of the main track A, the pivoted switch-track A², and the guides a a, arranged to operate together, substantially as and for the purposes set forth.

17. In a conveyer apparatus, the combination of the switch-track A', the double stop-catch B² B³, and the jointed elevator-bar D², arranged to operate substantially as and for the purposes set forth.

18. In a conveyer apparatus, the combination, substantially as set forth, of a car way or track, a car having a laterally-projecting finger or lug, such as F' or F², and a rave, F, arranged with relation to the track and the said projecting lug substantially as shown, so that it will come in contact with the said lugs under certain conditions, as named, and check the speed of or entirely stop the car by frictional action.

19. In a conveyer apparatus, the combination, substantially as set forth, of a suspended track or way having curves therein, a car with its trolley on said track and its receptacle hanging pendent below it, guide-raves adjusted in conformity to said track at its curves, and friction-rollers on said car in position to act on said raves and prevent the car-body or receptacle from swinging out centrifugally as the car passes around said curves.

20. In a conveyer apparatus, the combination, substantially as set forth, of the main track having the curved track-bar A⁴, the hangers a³, the guide-rave A⁵, and the car H, having friction-rollers H³.

21. In a conveyer apparatus, the combination, with the track A and cars H, having wheels H' and H², of the wire K, arranged below the track and inclined, as shown, so as to wedge in between the said upper and lower wheels and stop the movement of the car.

22. In a conveyer-apparatus track, the combination of the track-wire A, having curved track A⁴, and the curve-track seat-iron I, having eyes at each end for attaching the track-wire and the guy-wire, and a seat for the curve-track.

23. In a conveyer-apparatus car, the combination, with the tripping-wheels and the sliding frame-piece on which they are journaled, of an adjustable catch-trigger, and a scale showing the station-numbers by which to gage the adjustment of said trigger, substantially as and for the purposes set forth.

In testimony whereof I affix my signature in presence of two witnesses.

GEO. C. BLICKENSDERFER.

Witnesses:

JNO. K. HALLOCK,
ROBT. H. PORTER.
